UNITED STATES PATENT OFFICE.

HERBERT H. RUSSELL, OF NEW HAVEN, CONNECTICUT, ASSIGNOR TO THE GREIST MANUFACTURING COMPANY, A CORPORATION OF CONNECTICUT.

SEWING-MACHINE RUFFLER.

1,261,628.

Specification of Letters Patent. Patented Apr. 2, 1918.

Application filed May 7, 1917. Serial No. 167,029.

To all whom it may concern:

Be it known that I, HERBERT H. RUSSELL, a citizen of the United States, residing at New Haven, in the county of New Haven 5 and State of Connecticut, have invented or discovered certain new and useful Improvements in Sewing-Machine Rufflers, of which the following is a specification, reference being had therein to the accompanying drawing.

10 This invention relates to that class of sewing machine rufflers which are adapted for use in making a ruffle or gather at each stitch, or at each reciprocation of the needle-bar of the sewing machine, or to make a ruffle or gather at longer intervals, as at each 15 five reciprocations of the sewing machine needle-bar; these rufflers being generally known as "five-stitch" rufflers, although they 20 may be constructed to make a ruffle or gather either at each stitch or at a greater or lesser number of stitches than five. The present invention has for its object to simplify the construction of rufflers of this class.

25 In carrying the present invention into effect a shiftable pawl-lever is employed, in connection with a ratchet wheel having deep and shallow notches, as heretofore, and which pawl-lever coöperates with a pendulous lever by which the ruffling blade is actuated; this shiftable pawl lever and its co-operating parts being of such construction 30 that the pawl carried by said lever may engage the teeth of the ratchet wheel and a shoulder of the pendulous lever when "five-stitch" ruffling is to be performed, or may be shifted to a position to engage only the shoulder of the pendulous lever when plain work is to be done, or when a ruffle or gather 35 is to be made at each stitch, in which latter case the ratchet wheel will be at rest. Also, if desired, the shiftable pawl-lever may be moved to a position in which the pawl will not engage the teeth of the ratchet wheel, 40 and in such case the ruffler may be thrown out of operation without removing it from the sewing machine, if it be desired to do plain sewing only.

45 In the accompanying drawing, Figures 1 and 2 are opposite side views of a ruffler embodying the present invention. Fig. 3 is a plan view and Fig. 4 an end view of the same. Fig. 5 is a detail plan view showing the shiftable pawl-lever in full and dotted

line positions. Fig. 6 is a detail view of the 55 ratchet-wheel.

Referring to the drawing, 12 denotes the body of the frame of the ruffler which is preferably provided with an integral attaching portion or shank 13 by which it 60 may be secured to the presser bar of a sewing machine, in substitution of an ordinary presser foot. The forked operating lever 14, which is adapted to engage a pin or stud on the needle-bar of the sewing machine, is pivotally mounted on a stud or pin 15 riveted or otherwise permanently attached to an upright portion of the frame 12. Also pivotally mounted on said stud or pin 15 is a pendulous or secondary lever 16 70 to the lower end of which the ruffling blade carrier 17 is jointed, the said lever 16 being provided at its top with a shoulder 18. The ruffling-blade 17^a is attached to the carrier 17 as usual. A ratchet wheel 19, having 75 shallow notches 20, affording short radial teeth, and two deeper notches 21, affording longer radial teeth, is mounted for rotation on the stud or pin 15.

80 The operating lever 14 is constructed with a bent-over or horizontal portion 22 to which is attached a pin or rivet 23 passing through a portion of a shiftable pawl-lever 24 carrying a pawl 25 preferably formed integral with said lever and adapted to engage the 85 teeth of the ratchet wheel 19 and the shoulder 18 on the pendulous lever 16, when "five-stitch" ruffling is to be done; or the said pawl-lever may be shifted laterally to the position denoted by the dotted lines *x* in 90 Fig. 5, so that the pawl 25 will engage only the said shoulder 18 of said pendulous lever 16, when plain ruffling or gathering is to be done; or, if desired, the said shiftable pawl-lever may be moved to the position indicated 95 by dotted lines *y* in Fig. 5, so that the pawl 25 cannot engage said shoulder 18 on the pendulous lever 16, and the ruffling blade will then be thrown entirely out of action. When the shiftable pawl-lever 24 is in the 100 position denoted by full lines in Fig. 5 the pawl 25 will be held out of engagement with the shoulder 18 on the pendulous lever 16 when said pawl rests in the shallow notches 20 of the ratchet wheel 19; but when the 105 said wheel is partially rotated to bring one of the deeper notches 21 of said ratchet-wheel beneath the said pawl the latter will

descend low enough to engage the said shoulder 18 of said pendulous lever and impart, through the said lever, a forward or ruffling stroke movement to the ruffling blade 17 and the ruffling blade 17^a attached to said carrier, on the upward movement of the operating lever 14. The pendulous lever 16 is provided with an arm 27 which will be engaged by an adjustable contact screw 28 carried by the operating lever 14 on the next downward movement of said lever after the ruffling blade has performed a ruffling stroke and thus retract, through the said pendulous lever 16, the ruffling blade carrier 15 and ruffling blade. The contact screw 28, is threaded in an ear 29 on the operating lever 14.

The shiftable pawl lever 24 is pivoted, so that it may be shifted laterally to different positions, on the pin or rivet 23, and the longer arm of said pawl-lever, carrying the pawl 25, is forced yieldingly downward by a coil spring 31 interposed between the lower head of said rivet and the shorter arm of said pawl lever, the latter being bent, as shown, so as to have a fulcrum bearing, slightly rearward of the said coil spring, on the lower surface of the bent-over or horizontal portion 22 of the operating lever 14. Thus the pawl 25 carried by the said pawl-lever will be yieldingly forced downward into engagement with the teeth of the ratchet wheel 19, so as to intermittently rotate the said wheel, and also so that it will, at proper times, be depressed so as to engage the shoulder 18 on the pendulous lever 16. As the pawl-lever 24 is yieldingly forced downward by the spring 31 the pawl 25 will ride backward easily over the teeth of the ratchet-wheel 19 when the operating lever 14 rises, backward rotation of the said ratchet-wheel, when the said pawl is retracted, being frictionally prevented, as is common in five-stitch rufflers. If it be desired to throw the ruffler out of action without removing it from the sewing machine this may be done, as heretofore stated, by shifting the pawl-lever laterally or horizontally to the position denoted in dotted lines *y* in Fig. 5, the pawl 25 being at this time in position so that it cannot engage the shoulder 18 on the pendulous lever 16. The term "laterally" as herein employed to describe the shifting movements of the pawl-carrier or pawl-lever 25 will be understood to mean in a direction transverse to the line of movement of the work or to the line of movement of the ruffling blade.

The shiftable pawl-lever 24 will be retained in the three positions referred to by the fork 32 formed on a rearward-extension of the operating lever 14, as will be understood from Figs. 4 and 5, so that accidental displacement of the said shiftable pawl-lever will be prevented when the said lever

is in either of the three positions denoted in Fig. 5. The said pawl lever will be prevented from being lifted too far by the horizontal bent-over part 22 on the said operating lever 14. 70

From the foregoing it will be understood that the present invention provides a "five-stitch" ruffler of very simple construction, in that some parts heretofore necessary in the constructions of rufflers of this character 75 are dispensed with by the use of the simple pawl-lever herein shown and described.

The feature, hereinbefore referred to, by which the ruffling blade may be thrown out of action without removing the ruffler from 80 the sewing machine, or without disconnecting the operating lever 14 from the needle-bar of the sewing machine, is a desirable feature in sewing machine rufflers in that the range of work, including a ruffling operation, is greatly widened. For example, it sometimes occurs that it is desirable to do plain stitching between groups of ruffles or gathers (with or without removing the ruffling strip, which may, if desired, be 85 stitched down by plain sewing) without removing the ruffler from the sewing machine; and this can readily be effected, with the present improved ruffler, simply by shifting the pawl lever laterally to the position denoted by dotted lines *y* in Fig. 5, as hereinbefore explained. When the pawl lever is in the position just referred to the pawl 25, carried by said lever, is in an inoperative relation both to the ratchet-wheel 90 19 and to the shoulder 18 of the pendulous lever 16. This capability of throwing the ruffling blade out of action without dismounting or disconnecting the ruffler from the sewing machine is therefore an important and valuable one. 100

Having thus described my invention I claim and desire to secure by Letters Patent:

1. In a sewing machine ruffler, the combination with a ruffling blade and means, comprising a pendulous lever provided with a shoulder, for operating said ruffling blade, of a ratchet wheel having deep and shallow notches, and a shiftable pawl-lever adapted to be moved transversely to the plane of movement of the said pendulous lever so as to occupy different lateral positions relative to said ratchet wheel. 110
2. In a sewing machine ruffler, the combination with a ruffling blade and means, comprising a pendulous lever provided with a shoulder, for operating said ruffling blade, of a ratchet wheel having deep and shallow notches, and a shiftable lever adapted to be moved transversely to the plane of movement of said pendulous lever so as to occupy different lateral positions relative to said ratchet wheel, said shiftable lever having a pawl formed integral therewith. 120
3. In a sewing machine ruffler, the combi- 130

nation with a suitable frame, of an operating lever pivoted to said frame and having a turned-over or horizontal portion, a secondary or pendulous lever also pivoted to said 5 frame and having a shoulder, a ruffling blade operatively connected with said pendulous lever, a ratchet-wheel having deep and shallow notches, a shiftable pawl-lever pivotally attached to said turned-over or horizontal 10 portion of said operating lever so that it may be adjusted laterally to different positions, and means for retaining said pawl-lever in different positions of adjustment.

4. In a sewing machine ruffler, the combination with a suitable frame, of an operating lever pivoted to said frame and having a turned-over or horizontal portion, a secondary or pendulous lever also pivoted to said frame and having a shoulder, a ruffling blade 20 operatively connected with said pendulous lever, a ratchet-wheel having deep and shallow notches, a shiftable, spring-pressed pawl-lever pivotally attached to said turned-over or horizontal portion of said operating 25 lever so that it may be adjusted laterally to different positions, and means for retaining said pawl-lever in different positions of adjustment.

5. In a sewing machine ruffler, the combination with a suitable frame, of an operating lever pivoted to said frame and having a turned-over or horizontal portion, a sec- 30

ondary or pendulous lever also pivoted to said frame and having a shoulder, a ruffling blade operatively connected with said pendulous lever, a ratchet-wheel having deep and shallow notches, a shiftable, spring-pressed, pawl-lever pivotally attached to said turned-over or horizontal portion of 35 said operating lever so that it may be adjusted laterally to different positions, and means for retaining said pawl-lever in different positions of adjustment, said pawl-lever being bent so as to have a fulcrum bearing on the lower surface of said turned-over or horizontal portion of said operating 40 lever.

6. In a sewing machine ruffler, the combination with a ruffling blade, and its carrier, of a pendulous lever having a shoulder; a ratchet-wheel for governing the frequency 50 of operation of said ruffling blade, a pawl for intermittently rotating said ratchet-wheel and also arranged to engage said shoulder, when desired, and means for moving said pawl out of operative contact relation to said shoulder and ratchet-wheel 55 and for holding said pawl in an inoperative position.

In testimony whereof I affix my signature. 60
